CLAIM

We claim the ornamental design for a gaming table, as shown and described.

DESCRIPTION

FIG. 1 is a front, right, top perspective view of the gaming table;

FIG. 2 is a front elevational view of the gaming table, wherein the rear elevational view is a mirror image thereof; FIG. 3 is the left side elevational view of the gaming table, wherein the right side elevational view is a mirror image thereof;

FIG. 4 is a top plan view of the gaming table; and, FIG. 5 is a bottom plan view of the gaming table.

The broken lines in the drawings illustrate portions of the gaming table that form no part of the claimed design. The stippling in the drawings illustrates shading and not surface pattern.
